CLOCK

James H. Dunbar, Jr., Geneva, Ill., and
Clare E. Hodgman, Tuckahoe, N. Y.

Application September 16, 1949, Serial No. 5,028

Term of patent 14 years

(Cl. D42-7)

To all whom it may concern:

Be it known that we, James H. Dunbar, Jr., and Clare E. Hodgman, citizens of the United States, residing at Geneva, in the county of Kane and State of Illinois, and Tuckahoe, in the county of Westchester and State of New York, respectively, have invented a new, original, and ornamental Design for Clock, of which the following is a specification, reference being had to the accompanying drawing, forming part thereof.

In the drawing; Figure 1 is a top plan view of a clock, showing our new design; Figure 2 is a front elevational view of the clock of Figure 1; Figure 3 is a bottom plan view of the clock of Figure 1; Figure 4 is a side elevational view of the clock of Figure 1; Figure 5 is a cross-axial

view taken through axis 5—5, Figure 2, with the rear portion of the clock in elevation; and Figure 6 is a back elevational view of the clock.

We claim:

The ornamental design for a clock, as shown.

JAMES H. DUNBAR, JR.
CLARE E. HODGMAN.
